UNITED STATES PATENT OFFICE.

JAMES E. BRADY, OF NEW YORK, N. Y.

PARTITION.

Application filed August 12, 1922. Serial No. 581,309.

To all whom it may concern:

Be it known that I, JAMES E. BRADY, a citizen of the United States, residing in New York city, county of New York, 5 borough of Manhattan, and State of New York, have invented certain new and useful Improvements in Partitions, of which the following is a full, clear, and exact specification.

10 My invention relates to partitions and refers particularly to partitions containing tensioned plaster supporting means.

In the formation of plaster partitions, it is necessary to have a supporting means for 15 the plaster during its erection and numerous means have been devised in order to accomplish this result.

Devices of this character should be light in construction, economical of production, 20 easily varied in order to act as devices suitable for partitions of various shapes and thicknesses, convertible into supporting means for particularly desired plaster backings, readily erected into proper form and 25 capable of supporting the plaster material.

These and many other desirable properties are possessed by the device of my invention.

My invention comprises two supporting means, between which is laced one, or more, 30 continuous tensioned members.

The usual construction of my device consists of two supporting means fixedly carried by the side wall, or top and bottom supports, and one, or more, metallic wires, 35 or tapes, preferably the latter, passed alternately over supports in the two supporting means in a continuous extension from one side of the desired partition to the other, the wires, or tapes, being under tension.

40 The two supporting means may be of any desired formation as long as they are capable of being supported in place and possess means over which the wire, or tape, may be passed.

45 The wire, or tape, may be of any material and may be of rope construction, if desired, and for purposes of clearness and brevity, I will refer to this element of my device as the "continuous plaster support."

50 The means for carrying the continuous plaster support by the supporting members may be of any suitable formation, but I prefer the use of bolts for this purpose as they give a wide field of usefulness to my 55 device as will be explained later.

The erection of a partition by means of

my device is extremely simple and can be accomplished by the inexperienced, as all that is necessary is to fix the two supports in proper alignment with each other, lace in 60 the continuous plaster support and apply plaster.

My device has the further valuable property of being capable of use as a means of 65 producing partitions of any desired thickness irrespective of the width of the supporting members, thus allowing the use of single sized supporting members irrespec- 70 tive of the desired thickness of the partition.

My device is very light in weight but 75 possesses great strength for the support of the plaster load and is free from warping and twisting.

It is further capable of adaptation to 75 walls of all shapes and sizes.

A consideration of my specification and the accompanying drawings will show that the device of my invention possesses all of the above and many other valuable and 80 novel features.

In the accompanying drawings, illustrating modified forms of the device of my invention, similar parts are designated by similar numerals.

Figure 1 is a diagrammatic side view of 85 one form of my invention showing the several steps in its formation.

Figure 2 is a section through the line 2—2 of Figure 1.

Figure 3 is a section through the line 90 3—3 of Figure 1.

Figure 4 is a section similar to that of Figure 2, employing the use of burlap as a plaster backing.

Figure 5 is a broken vertical cross-section 95 showing a modified form of my device for producing a thicker partition.

Figure 6 is a broken vertical cross-section showing a modified form of my device for 100 producing a solid partition.

Figure 7 is a broken vertical cross-section showing a flat supporting means.

Figure 8 is a top plan view of Figure 7.

The particular form of the device of my invention, shown in Figures 1, 2 and 3 of 105 the accompanying drawings, comprises an upper supporting member 10 and a lower supporting member 11 formed from channel iron. Brackets 12, 12, fixedly attached to the supporting members 10 and 11 allow 110 of the maintaining of the supporting member against the sides 13, 13 during the forma-

tion of my device and the subsequent plastering operations. A plurality of bolts 14, 14 pass through aligned openings of the supports 10 and 11.

5 Two steel tapes, preferably perforated, 15, 15 are then introduced into the device as follows:—

10 The end of a tape 15 is fixedly attached to the end of the support 11 at 16 and carried upwardly, being fixedly attached to the side 13 at 17, 17. A loop of the tape is then made at the first bolt hole in the top support 10, a bolt 14^A inserted through the bolt holes and beneath the tape. The tape 15 is then carried over the bolt 14^B of the bottom support in the same manner, then upwardly over the bolt 14^C of the top support, omitting bolt 14^D and the lacing of the tape thus continued the length of the supports 10 and 11 and the end fastened to the side 13 at 18 and to the bottom support 11 at 19. The device thus formed is shown in the left-hand portion of Figure 1.

20 Adjacent strands of the tape 15 are tensioned by means of the wires 20, 20 which encompass two adjacent tape strands and are then fastened to a bolt 14 between the two bolts 14, 14 over which the tape has been passed. By this means any desired condition of tension may be obtained upon the tape 15.

25 It is to be noted that if the tensioning process be commenced at one end of the device, the tape 15 will pass readily over both its upper and lower bolts, thus producing a uniform tension throughout. The bolts may carry loose annular sleeves 32 to act as idlers for this movement of the tape, if desired. The device thus formed is shown in the central portion of Figure 1.

30 The device thus constructed comprises the two tensioned tapes 15, 15, passing over the bolts 14, 14 of the top support 10 and of the bottom support 11 and spaced from each other.

35 Into the space between the two tapes 15, 15, two series of plaster boards 21 and 22 are placed and supported in spaced relation to each other by a plurality of spacing blocks 23, 23. This formation is shown particularly in Figures 2 and 3.

40 Both sides of the device are then filled and covered with plaster 22, which extends outwardly from the plaster boards 21 and 22, imbedding the top and bottom supports and tape. The wall thus formed may be finished in any desired manner.

45 If it is desired to use burlap, or similar material, for the plaster backing, a perforated tape 15 is employed and the burlap 24 attached thereto by connecting it to the tapes by means of a plurality of fastening means, or nails, 25, 25, which pass through the overlapped burlap and the openings in the tape. The burlap, or similar, surface

may be used as a plaster backing if desired.

50 A means of using the same supports 10 and 11 for the production of a partition considerably thicker than the width of such supports is shown in Figure 5 in which the bolt 26 is considerably longer than the width of the supports, the tapes 15, 15 being carried by the bolts outside of the supporting members, washers 27, 27 being employed to maintain them in position. In this manner 70 any desired thickness of partition can be obtained from a single standard width support.

55 If a solid plaster partition is desired, the arrangement of parts is shown in Figure 6 80 in which the tapes 15, 15 are so close together as to abut upon the opposite faces of the plaster board 27.

60 It is not necessary to employ channel iron for the supporting members, as any shaped support may be employed which will carry the bolts for the support and tensioning of the tapes. One method of using flat iron supports is shown in Figures 7 and 8 in which the bolt 14 is maintained by a supporting plate 28 having the portions 29, 29 turned over and abutting upon the flat support 30, the portions 31, 31 of the supporting plate being extended outwardly with aligned holes therein for the introduction 95 of the bolt 14.

65 It is evident that the supporting means may be vertical instead of horizontal as shown.

70 It is further evident that the fastening members 12, 12 may be different in construction from those shown in the drawings, and I have found that wire gauze is adaptable for this purpose, as the application of plaster through the gauze and against the side walls 100 will hold the supporting means in position, thus preventing the necessity of boring into the side walls for the insertion of bolts or other supporting means, the gauze being fixedly attached to the supporting members 105 110 110 115 120 125 130 135 140 145 150 155 160 165 170 175 180 185 190 195 198 200 205 210 215 220 225 rial of parts as shown and described, as these are given simply as an example in order to clearly describe my invention.

What I claim is:—

- 5 1. In a partition, in combination, two aligned supporting members, a plurality of spaced parallel means carried by the top and bottom of each supporting member each capable of carrying a continuous plaster support, a continuous plaster support laced between the top and bottom carrying means of each supporting member and upon the carrying means, the two extremities of the continuous plaster support being fixed and means for tensioning the continuous plaster support. 70
- 10 2. In a partition, in combination, two aligned supporting members, means for fixedly attaching the supporting members to a wall, a plurality of spaced parallel means carried by the top and bottom of each supporting member each capable of carrying a continuous plaster support, a continuous plaster support laced between the top and bottom carrying means of each supporting member and upon the carrying means, the two extremities of the continuous plaster support being fixed and means for tensioning the continuous plaster support. 75
- 15 3. In a partition, in combination, two aligned supporting members, means carried by the supporting members capable of carrying a plurality of parallel plaster supports, a plurality of continuous plaster supports laced between the two supporting members in planes parallel to each other, the extremities of the continuous plaster supports being fixed and means for tensioning the continuous plaster support. 80
- 20 4. In a partition, in combination, two aligned supporting members, means carried by the supporting members capable of carrying a plurality of parallel plaster supports, a plurality of continuous plaster supports laced between the two supporting members in planes parallel to each other, the extremities of the continuous plaster support being fixed and means for tensioning the continuous plaster support. 85
- 25 5. In a partition, in combination, two aligned supporting members, means carried by the supporting members capable of carrying a plurality of parallel plaster supports, a plurality of continuous plaster supports laced between the two supporting members in planes parallel to each other, the extremities of the continuous plaster support being fixed and means for tensioning the continuous plaster support. 90
- 30 6. In a partition, in combination, two aligned supporting members, means carried by the supporting members capable of carrying a plurality of parallel plaster supports, a plurality of continuous plaster supports laced between the two supporting members in planes parallel to each other, the extremities of the continuous plaster support being fixed and means for tensioning the continuous plaster support. 95
- 35 7. In a partition, in combination, two aligned supporting members, means for fixedly attaching the supporting members to a wall, a plurality of spaced parallel means carried by the top and bottom of each supporting member each capable of carrying a continuous plaster support, a continuous plaster support laced between the top and bottom carrying means of each supporting member and upon the carrying means, the two extremities of the continuous plaster support being fixed and means for tensioning the continuous plaster support. 100
- 40 8. In a partition, in combination, two aligned supporting members, a plurality of spaced parallel revoluble means carried by the top and bottom of each supporting member each capable of carrying a continuous plaster support, a continuous plaster support laced between the top and bottom carrying means of each supporting member and upon the carrying means, the two extremities of the continuous plaster support being fixed and means for tensioning the continuous plaster support. 105
- 45 9. In a partition, in combination, two aligned supporting members, a plurality of spaced parallel revoluble means carried by the top and bottom of each supporting member each capable of carrying a continuous plaster support, a continuous plaster support laced between the top and bottom carrying means of each supporting member and upon the carrying means, the two extremities of the continuous plaster support being fixed and means for tensioning the continuous plaster support so that adjacent strands will be in parallel position to each other. 110
- 50 10. In a partition, in combination, two aligned supporting members, means for fixedly attaching the supporting members to side walls, a plurality of bolts carried by the supporting members perpendicular to the plane of the supporting members and a continuous plaster support laced between the two supporting members and over the bolts, the extremities of the continuous plaster support being fixed. 115
- 55 11. In a partition, in combination, two aligned supporting members, means for fixedly attaching the supporting members to side walls, a plurality of bolts carried by the supporting members perpendicular to the plane of the supporting members, a continuous plaster support laced between the two supporting members and over the bolts, the extremities of the continuous plaster support being fixed. 120
- 60 12. In a partition, in combination, two aligned supporting members, means carried by the supporting members capable of carrying a plurality of parallel plaster supports, a plurality of continuous plaster supports laced between the two supporting members in planes parallel to each other, the extremities of the continuous plaster supports being fixed and means for tensioning the continuous plaster support so that adjacent strands will be in parallel position to each other. 125
- 65 13. In a partition, in combination, two aligned supporting members, means carried by the supporting members capable of carrying a plurality of parallel plaster supports, a plurality of continuous plaster supports laced between the two supporting members in planes parallel to each other, the extremities of the continuous plaster supports being fixed and means for tensioning the continuous plaster support so that adjacent strands will be in parallel position to each other. 130

extremities of the continuous plaster support being fixed and means for tensioning the continuous plaster support.

12. In a partition, in combination, two aligned supporting members, means for fixedly attaching the supporting members to side walls, a plurality of bolts carried by the supporting members perpendicular to the plane of the supporting members, a tape 40
10 laced between the supporting members and over the bolts, the extremities of the tape being fixed and means for tensioning the tape.

13. In a partition, in combination, two aligned supporting members, means for fixedly attaching the supporting members to side walls, a plurality of bolts carried by the supporting members perpendicular to the plane of the supporting members, two tapes 45
15 laced between the supporting members and over the bolts in planes parallel to each other, extending approximately the length of the supporting members, the extremities of the tapes being fixed and means for tensioning each tape.

14. In a partition, in combination, two aligned supporting members, means for fixedly attaching the supporting members to side walls, a plurality of bolts carried by the supporting members perpendicular to the plane of the supporting members, two perforated tapes laced between the supporting members and over the bolts in planes 50
30 parallel to each other, extending approximately the length of the supporting members, the extremities of the tapes being fixed and means for tensioning each tape.

15. In a partition, in combination, two aligned supporting members, screen means

carried by each end of the supporting member for attachment to side walls, a plurality of bolts carried by the supporting members perpendicular to the plane of the supporting members, a plurality of perforated tapes laced between the supporting members and over the bolts, extending approximately the length of the supporting members, the extremities of the tapes being fixed and means for tensioning each tape.

16. In a partition, in combination, two aligned supporting members, means for fixedly attaching the supporting members to side walls, a plurality of bolts carried by the supporting members perpendicular to the plane of the supporting members, two tapes laced between the supporting members and over the bolts in planes parallel to each other, extending approximately the length of the supporting members, the extremities of the tapes being fixed and means applied to adjacent tape strands tensioning the tape.

17. In a partition, in combination, two aligned supporting members, screen means carried by each end of the supporting member for attachment to side walls, a plurality of bolts carried by the supporting members perpendicular to the plane of the supporting members, a plurality of perforated tapes laced between the supporting members and over the bolts, extending approximately the length of the supporting members, the extremities of the tapes being fixed and wire means applied to adjacent tape strands tensioning the tape.

Signed at New York city in the county of New York and State of New York, this 11th day of August, 1922.

JAMES E. BRADY.
